OTTO SPAHR, OF PHILADELPHIA, PENNSYLVANIA, ASSIGNOR, BY MESNE ASSIGNMENTS, TO MILWAUKEE GAS SPECIALTY COMPANY, OF MILWAUKEE, WISCONSIN, A CORPORATION OF WISCONSIN.

FLASH IGNITER FOR GAS BURNERS.

Application filed January 23, 1924. Serial No. 687,887.

My invention relates to lighters for gas stoves and more particularly to that type thereof which are commonly termed flash igniters and which either occupy a fixed position in the gas stove for igniting any one or more of a series of burners therein or are adjustably mounted in said gas stove for selectively igniting any one of said series of burners. The object of the present invention is to provide a novel arrangement whereby the flow of gas through the igniter is efficiently controlled in a simple and positive manner. A further object of the invention is to provide a simplified construction whereby the pilot light, customarily found in igniters of the type referred to, is economically maintained and efficiently controlled. Other objects of the invention will appear from the description hereinafter.

In the accompanying drawing, which illustrates an example of the invention without defining its limits, Fig. 1 is a side elevation, partly in section, of the lighter; Fig. 2 is a sectional elevation on an enlarged scale; Fig. 3 is an inverted plan view of Fig. 2; Fig. 4 is a detail section on the line 4-4 of Fig. 2 and Fig. 5 is a detail view of the controlling valve.

For the purpose of describing the invention I have chosen an igniter of the type which is generally arranged to swing in circular arcs to bring the firing head into cooperative relation with the gas burner which it is desired to ignite; it will be understood that this is only an example which is not intended to nor does it define the limits of the invention.

As shown in the drawing, the lighter comprises a supply tube 10 provided at its free end with a burner or nozzle 11 located in a firing head 12 of any suitable construction, said tube 10 having its other end in screw-threaded connection with the boss 13 of a hollow valve plug 14. The latter is rotatably mounted in a valve casing 15 in the well known way and is provided with a spring 16 which bears against the valve casing 15 with one end and against a head 17 carried by the valve plug 14 with its other end. In the preferred arrangement the head 17 is screwed upon a screw-threaded extension of a plug 14, so as to be capable of adjusting the tension of the spring 16; a stop 17^a is fixed upon said extension to limit the move-

ment of said head thereon and to prevent a binding of the parts. The valve casing 15 is connected by means of a branch pipe 18 with the header or main supply pipe 19 of the gas stove in the well known way. As shown in the illustrated example, the valve plug 14 is formed with an axial passage 20 communicating with a transverse channel 21 which at its outer end communicates with an annular groove 22 formed on the valve plug in registry with the axial passage 23 of the branch pipe 18 whereby the valve casing is connected with the supply pipe 19. The axial passage 20 at one end is formed with a valve seat 24 and connected with the interior chamber 25 of the valve plug, said chamber being of relatively larger diameter and open at its outer end and being also in communication with the boss 13 and consequently with the tube 10. The open end of the interior chamber 25 is closed by means of a screw-threaded bushing 26 in which the valve stem 27 is slidably mounted, said valve stem at its inner end being formed with a needle valve 28 adapted to co-operate with the valve seat 24 to control the flow of gas to the burner or nozzle 11. For the purpose of centering the stem 27 in the chamber 25 and to guide it in its movements in said chamber, a rectangular nut 29 is adjustably mounted upon said stem which is screw-threaded at its inner end to receive said nut, as shown in Fig. 4 the nut 29 is so dimensioned that its corners are in engagement with the wall of the chamber 25 and its sides spaced therefrom to form spaces for the passage of the gas when the valve is open. The valve 28 is maintained in and returned to its closed position by means of a spring 30 which surrounds the stem 27 and bears with its one end against said nut 29 and has its other end in engagement with a washer 31 loosely mounted upon said stem preferably within the bushing 26 as shown in Fig. 2. The washer 31 in turn abuts against a felt or corresponding packing 32 which surrounds the stem 27 within an interior recess with which the bushing 26 is provided, the inner surface of the aforesaid recess is bevelled at its outer end as shown at 26^a for the purpose to be more fully described hereinafter.

At its outer end, exteriorly of the valve plug 14, the stem 27 is provided with a head

33 which may comprise an integral part of said stem or be rigidly secured thereto as desired. On its under surface this head is provided with parallel grooves or recesses 33^a extending completely across the head as shown in Fig. 5. These recesses 33^a are located upon opposite sides of the stem 27 and are adapted to receive the forked end 34 of an operating handle 35, it being understood that each recess 33^a accommodates one member of said forked end. The handle 35 is pivoted at 36 upon a suitable lug 37 extending outwardly from the valve plug 14 as shown in Figs. 1 and 2. The outer surface 15 of the head 33 is flat and is adapted to engage the head 38 of a stop screw 39 adjustably mounted upon the valve plug 14 and projecting therefrom between the forked end 34 as shown in Figs. 2 and 3.

26 In order to maintain a pilot flame at the burner 11, the valve stem 27 is provided with an axial channel 40 which extends inwardly from the apex of the valve 28 and terminates at a seat 41 extending in a plane 25 at right angles to the axis of the stem at an intermediate point thereof. Exit apertures 41^a are located at diametrically opposite points of the stem 27 in close proximity to the seat 41 and establish communication between the channel 40 and the tube 10. With this arrangement a restricted amount of gas passes at all times, even when the valve 28 is closed, through the channel 40 to the apertures 41^a and thence to the chamber 25; from the latter the restricted amount of gas passes to the pipe 10 and the burner 11 and serves to sustain a pilot flame thereat. For the purpose of regulating this restricted flow of gas and to control the size of the pilot 40 light a valve 42 projects from the inner end of a screw 42^a which is adjustably mounted in the stem 27 and exteriorly thereof is provided with a head 43 for manipulating said valve; the free end of the latter is flat and, 45 in the one extreme position of said screw, is adapted to engage the seat 41 and thereby close the inner end of the channel 40 to completely cut off the supply of gas through the same. By adjusting said end of the screw 50 valve away from said inner end of the channel to a greater or lesser extent, the flow of gas through the same is regulated to increase or diminish the size of the pilot flame at will and to adjust it in a manner to conserve 55 the consumption of gas in an economical manner and to provide a pilot light of maximum and uniform efficiency.

60 The lighter is operated in the customary manner; that is to say, it may be swung in an arc having the plug 14 as a center, to bring the firing head 12 and with it the nozzle or burner 11 into co-operative relation with the burner which it is desired to ignite. After this adjustment has been had 65 the handle 35 is pivotally actuated in the

well known way to move the needle valve 28 in a direction away from the seat 24 whereby the amount of gas which reaches the nozzle or burner 11 and the pilot flame thereat is temporarily increased so that a 70 correspondingly enlarged flame is temporarily produced whereby the gas at the selected burner is ignited. As soon as the handle 35 is released, the valve will be returned to its normal position by the action 75 of the spring 30, in which position said valve is closed and the flow of gas to the burner is again reduced to that which passes through the axial channel 40 for sustaining the pilot light. As the handle 35 is manipulated to open the valve 28, the stem 27 will be moved lengthwise relatively to the bushing 26 and accordingly will compress the spring 30; the latter in turn will press 80 against the washer 31 and cause it to force 85 the felt or other packing 32 against the inclined interior surface 26^a of said bushing 26. This causes the packing 32 to be compressed against the inner wall of the bushing 26 and against the stem 27, this compression 90 against the elements referred to being increased by the action of the inclined surface 26^a on said packing. In this way an absolutely gas-tight sliding fit of the stem 27 in the bushing 26 is secured at the time when it 95 is most needed, that is when the valve 28 is open and the full supply of gas is passing to the burner 11. That is to say the further the handle 35 is manipulated to open the valve 28 and consequently the further the 100 latter is opened the more gas-tight will the packing 32 become.

The described arrangement of combined needle valve and pilot light valve permits the needle valve 28 to be firmly seated upon the seat 24 in the closed position and consequently avoids the formation of objectionable spaces in which dirt and foreign matter may become lodged and thus interfere with the proper operation of the device. At 105 the same time by reason of the fact that the needle valve positively engages the seat with a wedging effect the latter is maintained free from foreign matter. The described arrangement also avoids all necessity for the 110 provision of special passages for maintaining a pilot light in operation and reduces the construction to the utmost simplicity and at the same time, makes the regulation of the pilot light a positive and simple matter. The 115 latter is due to the fact that the outer end of the head 43 of the pilot valve 42 is, generally speaking, in a readily accessible location.

120 It will be noted that the guide nut 29 at 125 all points within its range of adjustment, is located near the end of the stem 27 in close proximity to the needle valve 28 thereof. The stem 27 is thus positively guided by the bushing 26 and the nut 29 at two points re- 130

spectively near its opposite ends whereby said stem is efficiently held in its intended axial alinement and is uniformly guided with a minimum of friction.

5 The recesses 33^a of the head 33 in which the members of the forked end 34 of the handle 35 are located serve to protect said members and at the same time, in co-operation therewith, prevent unintentional rotation of the stem 27 and its associated parts, whereby the adjustment of the device might be disturbed. By extending the recesses 33^a completely across the head 33 the latter may be connected with the forked end 34 with 10 special regard to the position of said head.

By adjusting the stop screw 39 to position its head 38 with respect to the head 33, the opening movement of the valve 28 may be automatically arrested at a predetermined 15 point; the extent of opening of said valve may thus be positively predetermined and an adjustment effected whereby waste of gas is prevented and a most economical operation of the burner consistent with efficient 20 results is automatically obtained.

In many cases, the construction of the gas stove and the arrangement of the parts thereof, makes it desirable to install the lighter therein in a reversed position or, in 25 other words, upside down with respect to the position illustrated in the drawing. It will be understood that the arrangement shown and described is capable of being utilized in such reversed position without in 30 any way reducing its efficiency and that the illustrated position is only an example which in no sense defines the limits of the invention.

Various changes in the specific form 35 shown and described may be made within the scope of the claims without departing from the spirit of my invention.

I claim:

1. A gas lighter comprising a valve cas- 40 ing connected with a source of gas, a valve plug rotatably mounted therein, a supply 45

tube carried by and communicating with said plug, a burner carried by said tube, a valve seat in said plug, a valve stem slidably mounted therein and projecting outwardly 50 beyond the same, a valve at the inner end of said stem co-operating with said seat to control the supply of gas to said burner, said valve stem having a restricted axial passage and communicating apertures for supplying 55 a restricted amount of gas to said burner to maintain a pilot flame thereat, a head on said stem exteriorly of said valve plug, said head having parallel spaced recesses extending across the same in diametric directions, 60 a handle pivoted on said plug and having a forked end projecting beneath said head into the recesses thereof for actuating said valve and for pivotally adjusting said valve plug and its associated elements relatively 65 to said casing, and a stop adjustably mounted upon said valve plug and adapted to be engaged by said head to arrest the opening of said valve at a predetermined point.

2. A gas lighter comprising a valve cas- 70 ing connected with a source of gas, a valve plug rotatably mounted therein, a supply tube carried by and communicating with said plug, a burner carried by said tube, a valve seat in said plug, a valve slidably 75 mounted therein to control the flow of gas to said burner, a recessed head connected with said valve stem and located exteriorly of said plug, a handle pivoted on said plug and having a forked end projecting beneath 80 said head into the recesses thereof for actuating said valve and for pivotally swinging said valve plug and its associated elements relatively to said casing and a stop screw mounted upon said plug and having 85 its head in the path of the recessed head of said valve for arresting the opening of said valve at a predetermined point.

In testimony whereof I have hereunto set my hand.

OTTO SPAHR.
